PRESSURE PUMP

Joseph M. Schmied, Chicago, Ill.

Application November 23, 1945, Serial No. 630,272

5 Claims. (Cl. 103—173)

1

My invention relates to multicylinder pumps, and more particularly to pressure pumps of the balanced type wherein one or more cylindrical bodies or piston barrels, are provided with a series of cylinders in which pistons are caused to reciprocate by means of a cam operating on the ends of the pistons.

The principal object of my invention is to provide a pump of this general character in which the pistons not only act to pump a fluid under high pressure, but also serve as the valve means thus eliminating the usual valves and materially reducing the number of parts necessary in the construction of the pump.

Another important object of my invention is to provide a pressure pump of the above character which is double acting, and wherein two series of pistons are simultaneously reciprocated by a single cam member so that bearing loads are substantially cancelled out.

Still another object of my invention is to construct a pressure pump wherein the pistons are returned by push pins acted upon by confined wobble plates, the construction being such that the pins are in constant engagement with the wobble plates and the ends of the pistons are in constant contact with the driving cam, which results in an extremely well balanced, and smooth running pump.

The nature of my improvements will be better understood when described in connection with the accompanying drawings, which illustrate a pressure pump embodying my said improvements and in which:

Fig. 1 is a central longitudinal section of my improved pump, parts appearing in elevation.

Fig. 2 is a cross-section through one side of the pump on a plane indicated by the line 2—2 of Fig. 1.

Fig. 3 is a cross-section through the opposite side of the pump on off-set planes indicated by the line 3—3 of Fig. 1 looking in the direction of the arrows.

Fig. 4 is a developed view showing the progressive action of one set or series of the pump pistons.

Fig. 5 is a perspective view of one of the shoe plates used between the crowned end of the pistons and the driving cam, and

Fig. 6 is a perspective detail of one of the piston barrels looking toward the transfer conduits or passageways.

In the embodiment of my invention illustrated, the pump casing is designated as a whole by the

2

reference character A, and is formed by two identical halves indicated at 10 and 12 held together by studs 14 and nuts 16, the studs being received by holes 18 in the abutting flanges 20—20, as clearly shown in Figs. 1 and 2. Half 10 of casing A is formed with a cylindrical bore 22 to snugly receive the cylindrical piston body or barrel 24 and barrel end plate member 26, the latter being located between the body 24 and end wall 28 of casing half 10 as best shown in Fig. 1.

It will be further observed from Fig. 1 that piston barrel 24, barrel plate member 26 and end wall 28 are centrally bored to receive a bushing 30, and end 32 of the cam shaft B, while piston

body 25, plate member 27, and end wall 29 of casing half 12, are similarly provided with a central bore to receive the bushing 31 and end 33 of the cam shaft B. Piston barrel 24 is supplied with a series of spaced horizontal through bores or cylinders 35, within which a set of pistons 34 are reciprocated by face F of cam C in a manner presently disclosed. Cam C may be termed a driving inclined wobble plate. The outer end of cylinders 35 are connected by conduits 36 formed in the body 24 with the exception of the uppermost cylinders (Fig. 4) located adjacent the outlet port D and inlet port E formed in the casing half 10. There is also provided shallow clearance grooves 38, in the plate member 26, which

are in axial alignment with their respective cylinders and of a diameter to receive the outer ends of pistons 34 when they pass beyond the conduits 36 in a manner and for reasons later explained in connection with the valve arrangement. For each piston 34 there is a push pin 40. These pins are received by aligned holes in the plate 26, and end wall 28, to contact the inner surface 41 of wobble plate 42. The wobble plate is enclosed within a cap 44, secured to the end wall 28 by screws 46.

Piston barrel 25 (shown to the right in Fig. 1) is similarly provided with a series of spaced horizontal through bores or cylinders 37, within which a set of pistons 39 are reciprocated by the face G of cam C. The outer end of cylinders 37 are connected by transfer passageways or conduits 43, formed in the piston barrel 25 adjacent the barrel plate 27, with the exception of the uppermost cylinders located adjacent the outlet port D' and inlet port E' formed in the casing half 12. Shallow clearance grooves 45 in plate member 27 are in axial alignment with their corresponding cylinders 37 and of a diameter suitable to receive the outer ends of pistons 39 when they pass be-

40

45

50

55

yond the conduits 43. For each piston 38 there is a push pin 47, and these pins pass through aligned holes in the plate 27 and end wall 28 to contact the inner surface 49 of wobble plate 51. This wobble plate is also enclosed within a cap 53 secured to the end wall 28 by screws 55. It will be noted from Fig. 1 that end 33 of cam shaft B passes through a hole in wobble plate 51 and an opening in cap 53 which is made leak-proof by sealing means such as indicated at 54.

In Fig. 5 I have shown one of the sliding shoes used between each piston and the driving cam C. These shoes preferably comprise hardened disks 56, one face of which is flat to slidably engage the faces of driving cam C, and its other face being concaved to conform with and receive the crowned ends 58 of pistons 34 and 39 respectively. A central oil hole 60 is supplied in each shoe, as shown, to allow oil to pass from one face to the other of the shoe to lubricate its sliding movement relative to the cam and pistons.

Returning now to Fig. 4, wherein is shown a development of piston barrel 24, barrel plate 26, end wall 28, and the series of pistons 34, it will be observed that said pistons are given a wave-like motion by cam face F of cam C when the cam shaft B is rotated in the direction indicated by arrow 11. As shown in this view the highest rise of cam face F is between the pistons 34.1 and 34.7, and when in this position said pistons will have reached the end of their outward stroke to close the inlet port E and outlet port D respectively, and a complete filling of fluid between said pistons has taken place.

As the cam C is rotated further in the direction indicated by arrow 11 (Fig. 4) the highest rise of cam face F leaves piston 34.7 and approaches piston 34.1. Thus piston 34.7 will begin its discharge stroke and simultaneously start to uncover discharge port D. Upon still further movement of the cam C, pistons 34.1 to 34.7 will be progressively moved through a pressure stroke and a suction stroke. To state it another way, for each rotation of the cam C, each piston of the series 34 and 39 will be moved through a pressure stroke and a suction stroke.

It will now be understood that when the lowest point of cam face F is between pistons 34.1 and 34.7, piston 34.4 will be opposite the highest rise of cam F and at the end of its pressure stroke thus dividing the transfer conduits or passageways 36 midway the inlet and discharge ports E and D, and both of said ports will be open at this position of cam C. The pumping action of the series of pistons 39, brought about by the cam face G of cam C is identical to that just described in connection with the series of pistons 34 acted upon by cam face F of cam C, and for this reason will not be repeated. The pistons each successively close the transfer conduit for a time interval at the end of the piston pressure stroke to insure flow from the inlet to the outlet port. Suffice it to say that when piston 34.1 of the series 34 is opposite the low point of cam face F, piston 39.1 of the series 39 is opposite the low point of cam face G, and that all other pistons of the two sets are in progressively complementary positions.

It is believed that operation of the push pins 40 and 47 for pistons 34-39 respectively will be apparent from a study of Fig. 1. As the pistons 34-39 are progressively reciprocated by cam C the push pins 40-47 will be likewise progressively reciprocated, and through the wobble plates 42-51 return of the pistons are effected

by the conventional and well known wobble plate action.

Mention has already been made of the fact that no valves are used in my improved pump aside from the pistons themselves. For an explanation of this novel valve arrangement attention is again directed to the developed view of Fig. 4 wherein it will be recalled the pistons 34.1 and 34.7 are shown at the end of their outward stroke, ports E and D are closed, and the pump is completely filled. In other words, all of the transfer passages 36 are in communication with one another as shown in this figure. Now as the cam C is rotated in the direction indicated by arrow 11, the highest rise of cam face F will approach piston 34.2 causing it to move outwardly (Fig. 1) or downwardly (Fig. 4) and when said highest rise of cam face F is opposite said piston 34.2 its outer end will be seated in its associated clearance groove 38. Any oil trapped between the end of piston 34.2 and its clearance groove 38 will be discharged or permitted to escape through the notch-like cavity 38.1 into the adjacent transfer conduit 36 on the pressure side of piston 34.2.

Similarly, when the highest rise of cam face F is opposite piston 34.3 its outer end will be seated in its associated clearance groove 38 and so on as the cam C is rotated. From this it follows that when piston 34.3 is seated in its clearance groove 38, in the barrel plate 26, pistons 34.1 and 34.7 will have commenced their inward travel to uncover the inlet port E and discharge port D respectively, and that fluid on the pressure side of piston 34.3 will be forced out the outlet port D while fluid on the suction side of said piston 34.3 will be drawn in through the inlet port E. It will now be observed that the pistons opposite the highest rise of the cam faces F and G of cam C will be the dividing point between the suction side and discharge side of the pump, and as the cam C continues to rotate, this dividing point progressively changes.

It has been found that due to this construction, extremely high pressures can be built up by the pumping action of the pistons, and since the pump is double acting, bearing loads are substantially balanced or cancelled out completely.

50 The improved multi-cylinder pump or compressor herein described besides being of an extremely compact and simple construction and capable of producing high pressures, has the important advantage that the working stresses are distributed evenly and at a large number of points which accounts for the smooth working and increased useful life of the pump.

Still another and important advantage of my improved pump structure is found in the reduction of pulsations in the delivery of the pumping fluid which in a great measure is brought about by the absence of separate valves and the novel valve arrangement disclosed herein.

While I have shown and described a particular embodiment of my invention, it will be readily understood by those skilled in the art that variations may be made in the construction disclosed without departing from the basic features of my invention. I therefore do not wish to be limited to the precise construction disclosed, but wish to include within the scope of my invention all such modifications and variations which will readily suggest themselves.

What I claim as new and desire to secure by Letters Patent of the United States is:

1. In a multicylinder pump, the combination of a casing having a cylindrical bore, a cylinder body and barrel plate fitting in the cylindrical bore, cylinders in said cylinder body which are axially extending cylinder bores located at radii of equal lengths from the cylinder body axis, reciprocable pistons in the cylinders, a transfer conduit in the cylinder body connecting said cylinders, a partition between two adjacent cylinders, an inlet in communication with one of the two adjacent cylinders and an outlet in communication with the other of the two adjacent cylinders, said inlet and outlet also passing through the casing wall, thereby providing inlet and outlet ports clearance grooves in said barrel plate in axial alignment with said cylinders, a confined wobble plate housed within said casing, a push pin for each piston mounted for reciprocable movement in aligned bores in the barrel plate and casing end wall, and acted upon by said wobble plate to move said pistons in one direction, a cam shaft rotatably mounted in the end wall of said casing, and a driving inclined wobble plate fixed for rotation on said shaft and having its inclined face adjacent the ends of said pistons in parallel relationship with the plane of the confined wobble plate face so as to impart a progressive reciprocating motion to said pistons and their respectively associated push pins in a direction opposite to that imparted to the pistons by said confined wobble plate, the pistons each successively closing the transfer conduit for a time interval at the end of the piston pressure stroke to insure flow from the inlet to the outlet port.

2. In a multicylinder pump, the combination of a casing having a cylinder body portion with cylinders therein, reciprocable pistons in the cylinders, a transfer conduit in the cylinder body at one end thereof connecting said cylinders, a partition between two adjacent cylinders, an inlet in communication with one of the two adjacent cylinders and an outlet in communication with the other of the two adjacent cylinders, said inlet and outlet also passing through the casing wall, thereby providing inlet and outlet ports clearance grooves at the ends of each cylinder extending beyond said transfer conduit, a confined wobble plate housed within said casing, a push pin for each piston mounted for reciprocable movement in the casing end wall and acted upon by said wobble plate to move said pistons in one direction, a cam shaft rotatably mounted in the end wall of said casing, and a driving inclined wobble plate fixed for rotation on said shaft and having its inclined face adjacent the ends of said pistons in parallel relationship with the plane of the wobble plate face so as to impart a progressive reciprocating motion to said pistons and their respectively associated push pins in a direction opposite to that imparted to the pistons by said wobble plate, the pistons each successively closing the transfer conduit for a time interval at the end of the piston pressure stroke to insure flow from the inlet to the outlet port.

3. In a multicylinder pump, the combination of a casing having a cylinder body portion with cylinders therein, reciprocable pistons in the cylinders, a transfer conduit in the cylinder body at one end thereof connecting said cylinders, a partition between two adjacent cylinders, an inlet in communication with one of the two adjacent cylinders and an outlet in communication with the other of the two adjacent cylinders, said

inlet and outlet also passing through the casing wall, thereby providing inlet and outlet ports clearance grooves at the ends of each cylinder extending beyond said transfer conduit, a fluid escape passage leading from each clearance groove, a confined wobble plate housed within said casing, a push pin for each piston mounted for reciprocable movement in the casing end wall and acted upon by said wobble plate to move said pistons in one direction, a cam shaft rotatably mounted in the end wall of said casing, and a driving inclined wobble plate fixed for rotation on said shaft and having its inclined face adjacent the ends of said pistons in parallel relationship with the plane of the wobble plate face so as to impart a progressive reciprocating motion to said pistons and their respectively associated push pins in a direction opposite to that imparted to the pistons by said wobble plate, the pistons each successively closing the transfer conduit for a time interval at the end of the piston pressure stroke to insure flow from the inlet to the outlet port.

4. In a multicylinder pump, the combination of a casing having a cylinder body portion with cylinders therein, reciprocable pistons in the cylinders, a transfer conduit in the cylinder body at one end thereof connecting said cylinders, a partition between two adjacent cylinders, an inlet in communication with one of the two adjacent cylinders and an outlet in communication with the other of the two adjacent cylinders, said inlet and outlet also passing through the casing wall, thereby providing inlet and outlet ports clearance grooves at the ends of each cylinder extending beyond said transfer conduit, a notch-like fluid escape passage leading from each clearance groove, said notch-like fluid escape passage being in direct communication with said adjacent conduit, a confined wobble plate housed within said casing, a push pin for each piston mounted for reciprocable movement in the casing end wall and acted upon by said wobble plate to move said pistons in one direction, a cam shaft rotatably mounted in the end wall of said casing, and a driving inclined wobble plate fixed for rotation on said shaft and having its inclined face adjacent the ends of said pistons in parallel relationship with the plane of the wobble plate face so as to impart a progressive reciprocating motion to said pistons and their respectively associated push pins in a direction opposite to that imparted to the pistons by said wobble plate, the pistons each successively closing the transfer conduit for a time interval at the end of the piston pressure stroke to insure flow from the inlet to the outlet port.

5. In a multicylinder pump, the combination of a casing having a cylinder body portion with cylinders therein, reciprocable pistons in the cylinders, a transfer conduit in the cylinder body at one end thereof connecting said cylinders, a partition between two adjacent cylinders, an inlet in communication with one of the two adjacent cylinders and an outlet in communication with the other of the two adjacent cylinders, said inlet and outlet also passing through the casing wall, thereby providing inlet and outlet ports clearance grooves at the ends of each cylinder extending beyond said transfer conduit, means located within said casing to actuate said pistons progressively in a progressive reciprocating motion to provide a suction stroke of said pistons, and means cooperatively associated with said first named means located within said cas-

ing progressively to actuate said pistons to provide a pressure stroke therefor, the pistons each successively closing the transfer conduit for a time interval at the end of the piston pressure stroke to insure flow from the inlet to the outlet port.

JOSEPH M. SCHMIED.
